UNITED STATES PATENT OFFICE.

JAMES EVANS, OF PHILADELPHIA, PENNSYLVANIA.

SHED FOR DRYING BRICKS.

SPECIFICATION forming part of Letters Patent No. 249,144, dated November 1, 1881.

Application filed September 29, 1879.

To all whom it may concern:

Be it known that I, JAMES EVANS, of South Broad street, Philadelphia, Pennsylvania, have invented a new and useful Improvement 5 in Sheds for Drying Bricks, of which the following is a specification.

My invention relates to an apparatus for protecting green bricks made of tempered clay from the weather while drying; and it consists 10 in a skeleton covered rack having removable shelves, which are made to slide in sidewise upon end cross-pieces. The shelves are entered from each side and are placed one over the other. In this position all the bricks are easily 15 turned by the workmen, who pass up and down between the drying-sheds. These shelves, having been removed from the rack, are covered with raw bricks and then replaced in the rack, where the bricks are protected from rain-storms and 20 other injury by the weather until dried sufficiently for the kiln.

Figure 1 is a side elevation of the skeleton-rack. Fig. 2 is a cross-section through the racks as they stand in the yard. Fig. 3 shows 25 one shelf and bricks in perspective.

The rack consists of a ground-frame, B, vertical upright posts C, a roof, D, removable shelves E, resting on strips H, and a stop, K.

M represents the bricks on their flat sides 30 m' as set on edge.

In the manufacture of bricks from tempered clay the bricks have been removed from the mold and placed upon the floor of the yard, exposed to the cracking influence of the sun and 35 frost, and the washing by storms and heavy rains. Millions of bricks are annually destroyed in this way, either while they are laid flat on the yard-floor or when hacked into stacks. The shelves, having been removed 40 from the rack, are covered with raw bricks just from the mold to about six in number to each

shelf. The bricks are placed on the shelves either at the machine or wheeled to the rack and there placed on the shelves, which have been previously removed. The shelves are 45 then replaced in the rack, as shown at M, and when the bricks are sufficiently dry they are edged up, as shown at m', and remain until removed to the kiln.

By my construction of a drying-rack sufficient room is provided for the operator to turn the bricks and "pat" the same while standing outside of the shed. Traps may be used with these racks, as they have been used to protect bricks when hacked into stacks, and the racks 55 can be braced at the top one to the other. By these means the bricks are protected from the cracking influence of the sun, and injury by frost or storm, or the washing by heavy rains, and much less floor-space is needed during the 60 drying of bricks.

I am aware that sheds for drying green brick have been made of uprights arranged at the four corners of a rectangle, provided with notches and supporting an inclined roof, the 65 rails being fixed in said notches, and a series of transverse removable drying-boards extending across the shed and resting with their ends upon the side rails, and such I do not claim.

I claim—

The covered skeleton-rack herein shown for drying green bricks, consisting of the combination of a ground-frame, vertical posts, roof, removable sliding shelves resting on strips, and stops for limiting the sliding movement of 75 said shelves, all arranged substantially as specified.

70 JAS. EVANS.
